UNITED STATES PATENT OFFICE.

JOHN F. BRADY, OF CHICAGO, ILLINOIS.

STEAM-TURBINE.

No. 807,057.

Specification of Letters Patent.

Patented Dec. 12, 1905.

Application filed September 12, 1904. Renewed May 15, 1905. Serial No. 260,589.

To all whom it may concern:

Be it known that I, JOHN F. BRADY, a citizen of the United States, residing at Chicago, in the county of Cook and State of Illinois, 5 have invented a new and useful Steam-Turbine, of which the following is a specification.

My invention relates to steam-turbines; and my object is to provide a construction particularly adapted to the use of high-pressure and superheated steam, and comprises 10 revolubly-mounted concentral wheels with faces of a substantially convex, conical, or some similar form, the face of one wheel being disposed close to and opposite the face of 15 the other wheel, and each of such faces provided with a number of separated rings of projecting vanes, of which the rings of vanes of one wheel are so disposed relative to the adjacent rings of vanes of the other wheel 20 that oppositely-disposed vanes may revolve in substantially the same plane, annular space, or zone; but one wheel with its vanes revolves in an opposite direction to the other wheel and its vanes, and on account of the 25 forms of the opposing faces of the wheels the opposing vanes have a greater length at the peripheral portions of the wheels than at the central portions, so that steam at high pressure admitted to an axial circular interspace 30 or steam-receptacle between the wheels, having outwardly-leading peripheral passage-ways for steam, will permit the latter to quickly expand and by virtue of impact and reaction serve to revolve the wheels in oppo- 35 site directions, as is hereinafter more fully described, the same being illustrated in the accompanying drawings, in which—

Figure 1 is an axial section of the operative parts except a portion of one end of the solid 40 shaft, upon which one of the vane-wheels is mounted, the supporting-frame and shaft-boxes, steam-shaft packings, and other parts being all shown in a vertical section. Figs. 2 and 3 are side elevations of the opposing 45 vane-wheels without the vanes, each wheel having a short portion of shaft attached thereto, an axial portion of Fig. 3 being shown broken away to illustrate an axial depression adapted to receive the axial steam-receptacle 50 projecting from the opposing face of the wheel in Fig. 2, the normal position of the receptacle being illustrated in Fig. 1. Figs. 4, 5, 6, 7, and 8 are side elevations and axial sections of the vane-wheels without the vanes,

to illustrate several modifications of the 55 form of the interspace between the vane-wheels adapted to give results similar to the form of the interspace shown in Fig. 1. Fig. 9 shows an elevation of part of the face of one of the vane-wheels, including several vanes, 60 and also three other vanes in cross-section, which latter are so disposed to clearly illustrate the relative disposition of the vanes of the opposing wheel, the arrows indicating the outward course of the centrally-admitted 65 current of steam for operating the vanes in opposite directions. Fig. 10 is an enlarged side elevation of three of the vanes shown in Fig. 2, to illustrate manner of attaching to the wheels, of which latter portions of each 70 are shown in section. Fig. 11 is a face elevation of a wheel similar to one shown in section in Figs. 1 and 2, having one side portion broken away and the space showing arrows to indicate the reverse motion of the alter- 75 nate rows of vanes, the vanes of the opposing wheel being shown in cross-section in the relative position they are fitted to occupy. Fig. 11 also shows the central steam-receptacle having a cylindrical form, with the end 80 or head thereof of concavo-convex cross-section, as seen in Fig. 1, the receptacle in Fig. 11 showing a peripheral side portion broken away to plainly show the tangentially-disposed outwardly-leading passage- 85 ways for steam directed against the concave face of the first axial circle of vanes of the opposite wheel, which vanes are shown in cross-section. Fig. 12 is a front elevation to illustrate a short section of a vane-base with the 90 vane made integral therewith. Fig. 13 is a side elevation of two vanes, shown with their bases mounted in the side of the wheel.

Similar numerals indicate like parts throughout the several views.

The frame 1 is provided with journal-boxes, in which are coaxially mounted two shafts 2 and 3. At the inner end of shaft 2 is secured a wheel 4, and at the inner end of shaft 3 is secured a wheel 5, the wheels being separated 100 sufficiently so that an interspace is formed. Secured to wheel 4, surrounding the axial portion thereof, is a steam-receptacle 6, having in this instance a concavo-convex head 7 and a peripheral series of tangential passage-ways 8 leading outwardly from the interior, as shown. There is an axial passage-way 9 through part of the length of shaft 2,

which serves for the passage of steam admitted through pipe 10 and radial holes 11 into axial receptacle 6.

The vanes 12 and 13 in this instance have 5 a concavo-convex or crescent shape in cross-section and are attached to and disposed on the faces of the wheels at an angle to radial lines, the concave faces of the vanes of one wheel subtending an angle to that of the 10 vanes of the opposite wheel when in the position shown in Fig. 1, and is indicated in Figs. 2, 3, and 4, so that, as before stated, the oppositely-disposed rings of vanes of one wheel may revolve in practically the same 15 plane as the rings of vanes of the opposing wheel, but each revolving in an opposite direction to the other.

In this instance to attain the best results in the use of steam of comparatively high 20 pressure and superheated, the faces of disks 2 and 3 are so formed that they are not parallel from the axial to the peripheral portion, but the interspace is wider at the peripheral than at the axial portion to permit the steam 25 to expand very rapidly in order to attain high results by the impact thereof successively against the opposing vanes in its outward passage. In Figs. 4 and 5 it is obvious that a similar result in steam expansion is 30 produced when the disks 14 and 15 are planes and the opposing disks 16 and 17 are either conical or convex in outline. Also a similar result is attained in the opposing convex disks 18 and 19 in Fig. 6 and in the opposing 35 concave and convex disks 20, 21, and 22 and 23 in Figs. 7 and 8, the general form of interspace between the disks in each of these instances being to permit the steam to very rapidly expand, and so it is obvious that this 40 interspace may assume a great variety of forms and be much greater or much less at the peripheral portion in proportion to the

central portion than is shown in Fig. 1 and yet attain a desirable result in transferring motion to the disks.

45

I claim as my invention—

1. In a steam-turbine having vane-wheels mounted with side faces thereof in proximity and forming an interspace, a steam-inlet at the central portion of the interspace, opposing sets of vanes projecting from the opposite wheels into the interspace, the latter being wider at the peripheral than at the central portion, for the purpose stated.

2. In a steam-turbine having vane-wheels 55 mounted with side faces thereof in proximity and forming an interspace, a passage-way for steam leading into the interspace at the axial portion of the wheels, opposing sets of vanes projecting from the opposite wheels into the 60 interspace, the interspace wider and the vanes longer at the peripheral than at the axial portions of the opposing wheels, for the purpose stated.

3. In a steam-turbine having vane-wheels 65 mounted upon separate revoluble shafts, the vane-wheels having side faces disposed in close proximity and forming an interspace; opposing sets of vanes projecting from the opposite wheels into the interspace, an axial 70 steam-receptacle connected with one of the vane-wheels outside of the shaft upon which this wheel is mounted, the receptacle provided with peripheral passage-ways, and the shaft around which the receptacle is mounted 75 provided with a passage-way leading to a steam-supply and into the axial receptacle.

In testimony whereof I have signed my name to this specification in the presence of two subscribing witnesses.

JOHN F. BRADY
